F. J. CLEMENCER,
AUTOMATIC AND CONTINUOUS FILM DISTILLATION APPARATUS
APPLICATION FILED DEC. 16, 1923

APPLICATION FILED DEO. 16, 1903.

UNITED STATES PATENT OFFICE.

FRANCIS J. CLEMENGER, OF BEAUMONT, TEXAS.

AUTOMATIC AND CONTINUOUS FILM DISTILLATION APPARATUS.

No. 829,258.

Specification of Letters Patent.

Patented Aug. 21, 1906.

Application filed December 16, 1903. Serial No. 185,424.

To all whom it may concern:

Be it known that I, FRANCIS J. CLEMENGER, a citizen of the United States, residing at Beaumont, in the county of Jefferson, State of Texas, have invented certain new and useful Improvements in Automatic and Continuous Film Distillation Apparatus, of which the following is a specification, reference being had therein to the accompanying drawings.

This invention relates to an automatic and continuous film distillation apparatus, and particularly to an apparatus designed to separate the distilled products according to their different volatility.

The invention has for an object to provide a construction embodying an independent heating means by which a film of oil may be subjected to different degrees of heat and the volatilized products conducted therefrom to a collector or separator from which these vapors are condensed according to their volatility.

The invention has for a further object to provide independent heating-chambers communicating with a single source of heat, whereby the products of combustion from the secondary chamber are conducted to the primary chamber, thereby maintaining in the primary chamber a lower degree of heat than in the secondary chamber, so that the products discharged from the primary chamber will be subjected to a greater heat upon their entrance into the secondary chamber.

Another object of the invention is to provide means for comminuting the material before its introduction into the heating-chambers and also an improved apparatus for effectually separating vapors into distillates relative to their volatility.

Other and further objects and advantages of the invention will be hereinafter set forth and the novel features thereof defined by the appended claims.

In the drawings, Figure 1 is a vertical longitudinal section through the plant. Fig. 2 is a horizontal section of the comminuter on the line 2 2 of Fig. 1, and Fig. 3 is a similar view of the separator on the line 3 3 of Fig. 1.

Like letters of reference refer to like parts in the several figures of the drawings.

The letter A designates a pump of any desired construction by which the liquid to be distilled is forced into the cylinder A', internally provided with a body of reticulated material A², such as fine-wire netting, which

surrounds the perforated inlet-pipe A³, by which a heated medium is introduced into the cylinder A', such as ordinary or super-heated steam or other suitable gas—for instance, any products of combustion. The cylinder A' constitutes a comminuter by which the liquid passing therethrough becomes finely divided and is changed from a solid liquid form to an extremely finely divided froth. This froth is discharged from the comminuter through the pipe A⁴, which extends within the primary heating-chamber B and is therein suitably perforated. This heating-chamber is provided with a series of pipes or flues B', through which the products of combustion passing to the stack B² are adapted to pass and are reversed in direction by means of the baffle-plates B³, B⁴, and B⁵, disposed at the opposite ends of the heating-chamber, as shown in the drawings. The upper portion of this chamber is also provided with a dome B⁶, from which the conducting-pipe B⁷ extends. At the lower portion of the heating-chamber a trapped conducting-pipe B⁸ is provided, by which the liquid which is not vaporized in the first chamber may be conducted to a second chamber C, which is provided with a fire-box C', and being the first still to be heated by the products of combustion maintains a higher temperature than the chamber B. The discharge-pipe B⁸ from the chamber B extends within the chamber C and is perforated, as at B⁹, for the purpose of discharging the liquid upon the heated flues C², through which the products of combustion from the fire-box C' are adapted to pass. The products are directed in opposite directions through the flues by means of baffle-plates C³ and C⁴ and finally discharged into the inner portion of the primary heating-chamber B by means of the connecting-pipe C⁵, thus providing the different temperatures by a single fire. The secondary heating-chamber C is provided with a dome C⁶, and a discharge-pipe C⁷ extends therefrom. The liquids which have not been vaporized within the secondary heating-chamber are conducted downwardly therefrom by the trapped pipe C⁸ to a suitable receiving-tank C⁹.

The discharge-pipes B⁷ and C⁷ each communicates with a separating or collecting chamber D of any desired character—for instance, as here shown, provided with arched resisting-plates D', supported upon lugs from the walls of the separator to permit passage

of the vapors around the plates, while the separator itself is inclosed within the air-jacket D² for the purpose of forming an air-chamber to maintain the same at a proper temperature, and dampers D³ are provided for the entrance of air into said chamber to alter the temperature thereof when found desirable. The discharge-pipe B⁷ communicates with the upper portion of this separator, while the pipe C⁷ communicates with the lower portion thereof, and the gases of different specific volatility or gravity are adapted to be removed therefrom by condensing-coils E, E', and E², communicating at different points in the height of the separator and discharging into the tanks F, F', and F², respectively. Each coil has a portion of its length extended through the condensing-chamber E³.

It will thus be seen that the entire operation is continuous and automatic, thus effecting a great saving of time and labor, while the products produced are superior to the result of the ordinary processes or methods, and the capacity of the apparatus is very largely increased, while the fuel consumed is correspondingly decreased. It will be seen that the liquid in its finely-divided condition is passed to the primary heating-chamber and there vaporized as a film by slowly flowing over heated pipes therein, so that the gases of one specific volatility may be conducted directly therefrom to the upper portion of the separator, while the heavier liquids not vaporized in the primary heating-chamber are carried to the secondary heating-chamber, where a greater degree of heat is applied and the vaporized portions conducted therefrom to the lower portion of the separator. The remaining heavy and viscous portion of the liquid then escapes from the secondary chamber.

Owing to the temperature prevailing in the separator or column D, which is regulated by the dampers D³, the gasoline vapors are constantly ascending in the separator and escape from the upper condensing-pipe E. The vapors which succeed the gasoline in boiling-point are of less volatility relatively to the temperature of the separator and escape therefrom through the condensing-pipe E'.

Referring to the apparatus shown, in which a continuous and automatic distillation is secured, the still B receives the crude oil from the comminuter A' at a density of 20° Baumé, (Texas crude.) In passing through still B the light hydrocarbons are volatilized, and the vapors therefrom issue through pipe B⁷ into the separator D, where the temperature is so regulated that the vapors do not fall below the second plate D' from the top. The oil in still B being deprived of its light constituents is reduced to a density of 22° Baumé and flows at this stage through the connection B⁸ into the still C. The stronger

fire beneath this still causes the heavier oils to be evaporated therein, and they are carried through the connecting-pipe C⁷ into the separator D at a lower point than the products of the first still. When the vapors from a single still are conducted directly to a condenser, an uneven distillate is secured, as in the most careful adjustment of the temperature in the still the vapors therefrom vary in character and density, dependent upon the variation in the temperature and also upon the character of oil introduced. Under these conditions all of the vapors are conducted to one condenser, giving an unsatisfactory product. In order to avoid this, the separator D is provided, and the conducting-pipe B⁷ discharges thereinto below the top, so that the lightest or gasoline vapors ascend to the condensing-pipe E, while the heavier vapors lie below the point of introduction of the pipe and are adapted to pass from the condensing-pipe E'. In the continuous process the oil from which the lighter vapors have been extracted passes to the second still at a higher temperature, and the vapors from this still also vary in density, so that the lighter ones therefrom ascend and commingle or contact with the heavier vapors from the first still, both of which are of approximately the same density and are conducted through the condensing-pipe E', while the heavier vapors from this latter still will be removed by the condensing-pipe E². This operation is effectually secured by the proper regulation of the temperature of the separator, which controls the vapors therein, while the resisting-plates prevent a general commingling and contamination of the gases within the separator. This latter result is also obviated to a large extent by the continued passage from the separator through the different condensing-pipes, so that there is a moving current of vapors within the separator during the operation of the stills. There is also some degree of condensation in the conducting-pipes and upon the plates D' within the separator, the products of which fall as a liquid to the bottom of the separator and are conducted therefrom by the pipe E². The use of this separator effects a continuous distillation with a better rectification of the different products and with the use of a materially smaller quantity of chemicals than are usually necessary in the manufacture of the different distillates.

While the apparatus is particularly adapted for the distillation of petroleum-oil and similar liquids, still it is designed for use with any character of liquid.

Having now described my invention and set forth its merits, what I claim, and desire to secure by Letters Patent, is—

1. In a distilling apparatus, a primary heating-chamber, a secondary heating-chamber subjected to a different temperature from

the primary chamber and receiving the liquid product therefrom, a separator, a chamber surrounding said separator, independent conducting-pipes from each of said heating-chambers connected with the separator at different points, and a series of condensing-pipes connected with said separator at different points in its height.

2. In a distilling apparatus, a primary heating-chamber and a secondary heating-chamber separate from each other and connected by a heat-passage, a fire-box beneath the secondary chamber, means for introducing material into the primary chamber, means for conducting material from the primary to the secondary chamber, means for removing unvaporized material from the secondary chamber, a separator, a communicating passage from each of the heating-chambers with the separator, and condensing-pipes communicating with said separator.

3. In a distillation apparatus, a primary heating-chamber and a secondary heating-chamber separate from each other and connected by a heat-passage, a fire-box beneath the secondary chamber, means for introducing material into the primary chamber, means for conducting material from the primary to the secondary chamber, means for removing unvaporized material from the secondary chamber, a separator, a communicating passage from each of the heating-chambers with the separator, and condensing-pipes communicating with said separator at different points in its height.

4. In a distillation apparatus, a primary heating-chamber and a secondary heating-chamber separate from each other and connected by a heat-passage, a fire-box beneath the secondary chamber, means for introducing material into the primary chamber, means for conducting material from the primary to the secondary chamber, means for removing unvaporized material from the secondary chamber, a separator, a communicating passage from each of the heating-chambers with the separator, condensing-pipes communicating with said separator at different points in its height, and independent collecting-receptacles for each of the condensing-pipes.

5. In a distillation apparatus, a primary heating-chamber and a secondary heating-chamber separate from each other and connected by a heat-passage, a fire-box beneath the secondary chamber, means for introducing material into the primary chamber, means for conducting material from the primary to the secondary chamber, means for removing unvaporized material from the secondary chamber, a separator, a communicating passage from each of said chambers with the separator, condensing-pipes communicating with said separator at different points in its height.

in its height, independent collecting-receptacles for each of the condensing-pipes, and an air-chamber surrounding said separator and provided with air-inlets at different points in its height.

6. In a distillation apparatus, a primary heating-chamber and a secondary heating-chamber separate from each other and connected by a heat-passage, a fire-box beneath the secondary chamber, means for introducing material into the primary chamber, means for conducting material from the primary to the secondary chamber, means for removing unvaporized material from the secondary chamber, a separator, a communicating passage from each of said heating-chambers with said separator, condensing-pipes communicating with said separator at different points in its height, independent collecting-receptacles for each of the condensing-pipes, an air-chamber surrounding said separator and provided with air-inlets at different points in its height, and resisting-plates disposed one above another and supported by lugs extending inward from the walls of the separator.

7. In a distillation apparatus, a plurality of heating-chambers, a separator communicating with the upper portions thereof to receive the vapors therefrom, a series of superposed resisting-plates supported within said separator, and a series of condensing-pipes disposed at different points in the height of the separator.

8. In a distillation apparatus, a plurality of heating-chambers, a separator communicating with the upper portions thereof to receive the vapors therefrom, a series of superposed resisting-plates supported within said separator, a series of condensing-pipes disposed at different points in the height of said separator, an air-jacket surrounding said separator, and air-inlets therein for varying the temperature within said jacket.

9. In a distillation apparatus, a primary heating-chamber having a series of flues, a pipe disposed within the same to discharge upon the flues, a secondary heating-chamber provided with a series of flues, a pipe disposed therein to discharge a feed of oil upon said flues, a trapped connection between the lower portion of the primary chamber and the pipe within the secondary chamber, a collecting-chamber, and independent means for conducting gas from each heating-chamber to different points in the height of said collecting-chamber.

10. In a distillation apparatus, a primary heating-chamber having a series of flues, a pipe disposed within the same to discharge upon said flues, a secondary heating-chamber provided with a series of flues, a pipe disposed therein to discharge a film of oil upon said flues, a trapped connection between the

lower portion of the primary chamber and the pipe within the secondary chamber, a comminuter provided with a body of reticulated material therein through which the liquid to be vaporized is passed before its entrance into the primary heating-chamber, a collecting-chamber, and independent means for conducting gas from each heating-cham-

ber to different points in the height of said collecting-chamber.

In testimony whereof I affix my signature in presence of two witnesses.

FRANCIS J. CLEMENGER.
